UNITED STATES PATENT OFFICE.

FREDERICK N. HUBBELL, OF SAN FRANCISCO, CALIFORNIA, ASSIGNOR TO DAVID R. CARRIER, OF SAN FRANCISCO, CALIFORNIA.

ORE CONCENTRATOR AND CLASSIFIER.

1,184,240.

Specification of Letters Patent. Patented May 23, 1916.

Application filed September 8, 1914. Serial No. 860,802.

To all whom it may concern:

Be it known that I, FREDERICK N. HUBBELL, a citizen of the United States, residing in the city and county of San Francisco, State of California, have invented a new and useful Ore Concentrator and Classifier, of which the following is a specification.

My invention relates to improvements in ore concentrators, and is adapted to both placer and quartz mining operations.

The object of my invention is to provide an ore concentrator and classifier wherein placer gravel, or combined pulverized rock and their other contained metallic constituents are automatically separated, and classified each gravity mineral by itself, and each gravity mineral automatically recovered by itself. I attain these objects by the mechanism illustrated in the accompanying drawings, in which—

Figure 1, is a top view of the entire machine. Fig. 2, is a longitudinal section 2—2, of Fig. 1; Fig. 3, is a transverse section through the oscillating pan and the stationary box on the line 3—3, of Fig. 1; Fig. 4, is a detailed view in section of the discharge openings in side of the pan showing method of raising or lowering the height of the same by an attached sliding plate, holding a tube.

Similar numerals refer to similar parts throughout the several views.

My improved ore concentrator and classifier consists essentially of a shallow pan, 1, wherein the sides 2, 3 and the bottom, 4, slope to a common point, 5 at the bottom of said pan, 1, said point 5 being in the usual construction of pan, 1, about one-third pan-length distance, more or less, from a given edge or end, 6, of pan 1.

One or more transverse partitions, 7, 8, 9, divide the pan, 1 into compartments 10, 11, 12. The partition, 7, nearest the edge or end, 6, of pan, 1 has at its lowest edge and at the center of said partition an opening 13, connecting one compartment, 10, with another compartment, 11. The transverse partition 8, next succeeding this has a similar opening, 14, or slot extending to a greater height than the opening, 13, in the first partition, 7, mentioned and the next succeeding transverse partition, 9, has a similar opening, 15, and successively higher than the one immediately preceding, and

so on. The portion of pan, 1, directly in front of said partitions 7, 8, 9, has beveled ridges, 16, 17, 18, 19, 20, running along the sloping bottom 4, of the pan 1, starting from the end, 21 of the pan, 1, and perpendicular to the transverse partitions, 7, 8, 9, said ridges 16, 17, 18, 19, 20, sloping from their centers to their sides and corresponding in bevel to the sides of pan, 1. On the sloping sides of compartments, 10, 11, 12, 65 formed by transverse partitions, 7, 8, 9, are openings, 22, 23, 24, leading into separate compartments of a stationary box, 25, connected therewith by freely-moving flexible tubing, 26, 27, 28. In compartments 29, 30, 70 31, of stationary box, 25, are small bucket elevators, 32, 33, 34, for discharging the contents thereof. The shallow pan, 1, is suspended in a suitable manner from supporting posts or standards 35, 36, 37, 38, so 75 that oscillations may be imparted to the same transversely by suitable mechanism, 39.

The operation of my improved ore concentrator and classifier is as follows: When sand, gravel, or mill pulp is conveyed through feed box 40, to pan 1, just in front of the series of transverse partitions 7, 8, 9, the oscillating motion of pan 1, combined with the sloping sides of ridges 16, 17, 18, 85 19, 20, causes a settling of the heavy components of said sand, gravel or pulp and the water fed with the material causes a flowing away of the lighter material through the lower or discharge end, 21, of pan 1, opposite transverse partitions 7, 8, 9. Each different gravity mineral separates and stratifies at the bottom of pan 1, and the different openings 13, 14, 15, at the lower edges of transverse partitions 7, 8, 9, 95 permit the classified delivery of different gravity concentrates by reason of the difference in height of these different openings 13, 14, 15, in each transverse partition 7, 8, 9. The result is that the compartment, 10, 100 farthest from discharge end, 21, of pan 1, will carry the heaviest gravity material; the next succeeding compartment, 11, will carry the next heaviest gravity material, and so on. The openings 22, 23, 24, in sloping 105 sides of compartments 10, 11, 12, regulate the height to which the classified material in any given compartment shall rise, and as it rises to level of openings 22, 23, 24, the oscillating motion of pan, 1, causes the 110

classified material in the compartments, 10, 11, 12, to drop into and be shaken through its individual tubing, 26, 27 or 28, into its compartment 29, 30 or 31, in the stationary 5 box 25, containing the small bucket elevators 32, 33 and 34. Said stationary box, 25, through a suitable stationary supply pipe, 41, is filled with water, whose regulated flow 10 maintains the level of water in said box, 25, in correspondence with the water level in the oscillating pan, 1, through the connecting tubes 26, 27, 28, thus causing no current 15 of water through said connecting tubes sufficient in force to prevent the proper dropping of the concentrated and classified material from the oscillating pan, 1, through the flexible tubes 26, 27, 28, into the compartments of the stationary box, 25.

Having thus described my invention, 20 which I claim is new, I desire to secure by Letters Patent of the United States:

A classifier and concentrator comprising

a shaking pan having a sloping bottom and side-walls forming a stratifying compartment and a plurality of collecting and discharging compartments beyond the stratifying compartment, the compartments being separated by transverse partitions, said partitions having ports at their lower ends, the vertical dimensions of said ports decreasing progressively away from the stratifying compartment, separate discharge conduits connected to the collecting compartments at progressively lower levels, and receiving means connected to each discharge 30 means adapted to maintain a hydrostatic head in the conduits corresponding substantially to the hydrostatic head in the pan.

In testimony whereof I affix my signature in presence of two witnesses.

FREDERICK N. HUBBELL.
